ELECTRIC HIGHWAY SIGNAL FLARE

John K. Lawlor, 19122 Bridwell St.,
Glendora, Calif. 91740

Filed July 19, 1967, Ser. No. 7,872

Term of patent 14 years

(Cl. D72—1)

FIG. 1.

FIG. 2.

FIG. 3.

FIGURE 1 is an elevational view of an electric highway signal flare, showing my new design;

FIGURE 2 is a top plan view thereof; and,
FIGURE 3 is a bottom plan view thereof.

I claim:

The ornamental design for an electric highway signal flare, substantially as shown.
